AUTOMOBILE JACK

Filed April 11, 1923

2 Sheets-Sheet 2

Fig. 3.

UNITED STATES PATENT OFFICE.

THOMAS WILLIAM BIBB, OF ELLensburg, WASHINGTON.

AUTOMOBILE JACK.

Application filed April 11, 1923. Serial No. 631,455.

To all whom it may concern:

Be it known that I, THOMAS W. BIBB, citizen of the United States, residing at Ellensburg, in the county of Kittitas and State of Washington, have invented certain new and useful Improvements in Automobile Jacks; and I do hereby declare the following to be a full, clear, and exact description of the invention, such as will enable others skilled in the art to which it appertains to make and use the same.

This invention relates to improvements in lifting jacks for automobiles and the like.

The object of the invention is to provide a device of the character indicated of an improved and simplified structure adapted to be carried in a compact form, and to use with the aid of the foot alone.

Further objects will more particularly appear in the course of the following detailed description.

The invention consists in the novel construction, arrangement, and combination of parts as hereinafter more particularly described and claimed.

Two sheets of drawings accompany this specification as part thereof, in which like reference characters indicate similar parts throughout.

Figure 1 is a horizontal cross section taken substantially medial the device;

Fig. 2 is a side elevation;

Fig. 3 is a vertical cross section showing one standard removed;

Fig. 4 is a fragmentary sectional view taken on line 4-4 of Fig. 3.

Fig. 5 is a fragmentary sectional view taken on line 5-5 of Fig. 3;

Fig. 6 is a transverse cross section of the handle joints.

In accordance with the present invention, a suitable base plate 1 is provided, to which is secured a frame 2, which may be conveniently formed from sheet metal 45 bent and stamped to provide two parallel spaced standard parts 3-3, provided with aligned vertically extending slots 4, and arcuately shaped pivot-bearing slots 9.

Between the standards 3-3 is slidably mounted a rack 5 having laterally disposed guide lugs 6 adapted to slide in the slots 4 and having upon one face thereof rack teeth 8. Secured to the top of the rack 5 is a suitable head 7 which may be pivotally or otherwise secured thereto.

Between the standards 3-3 and adjacent base 1 is mounted a lever 11 having laterally disposed pivot lugs 10-10 adapted to slide in the arcuate slots 9-9 of the standards. To the end of lever 11 adjacent rack 5 is pivoted a vertically extending dog 16, having a nose 19 adapted to engage and vertically elevate rack 5. Adjacent pivot lugs 10-10 but eccentrically disposed relative thereto is a pivot-bearing 13, disposed intermediate the axis of lugs 10-10 and the rack 5. Upon the pivot-bearing 13 is mounted vertically extending pawl 17, the nose 18 of which is adapted to engage teeth 8 above the nose 19 of dog 16. Dog 16 is connected with pawl 17 adjacent their rack engaging ends by means of a resilient member 22, preferably a spring bent into substantially W-shape, and having its ends secured as by lugs 20, 21 to the pawl and dog respectively. This spring is so proportioned and formed as to exert either a push or pull between the dog and the pawl, as will hereinafter more clearly appear in describing the operation of the device.

Mounted upon the inner face of one of the standards 3, or in any other suitable manner, is a stop lever 23 adapted to engage spring 22 to cause said spring to exert a push effect to both the dog and the pawl. Stop lever 23 is connected as by rod 25 with a lever 26 pivoted adjacent the bottom of standards 3-3, and provided with a slot adapted to receive one of the pivot lugs 10 of lever 11.

Hingedly connected to the outer end of lever 11, as by pivot 32 is a handle part 15, preferably formed of sections of sheet metal 30, stamped into U-shape cross section and connected by rule joints disposed with the shoulders 31 of the rule joints directed downwardly as is illustrated in Figure 1. These sections are formed so as to nest one within the other upon being folded inwardly, so that the entire handle may be folded upon itself and nested between the standards 3-3 as is illustrated in Fig. 3 by dotted lines.

In operation the jack in its lowered position as illustrated in the drawing is pushed under the automobile or other vehicle by means of handle 15 which operates to force lever 11 forwardly upon its pivot lugs 10-10 within slots 9-9 to the position illustrated in Figs. 2 and 3. By reason of

the rule joints connecting the handle sections the handle affords a rigid resistance to downward pressure, which may be exerted by the foot of the operator, thus rocking lever 11 upon pivot 10—10 and elevating dog 16 and rack 5. During this operation the push tension of spring 22 operating upon pawl 17 retains said pawl in contact with the rack to secure it in the position to which it is raised by the dog 16.

By reason of the eccentric pivoting of pawl 17 relative to lever 11 the weight of the load upon rack 5 will be transmitted through pawl 17 to lever 11 and upon the release of handle 30 by the release of the pressure of the operator's foot thereon pawl 17 will operate lever 11 to elevate handle 15 into operative position whereupon further pressure of the foot of the operator will repeat the operation and so on successively until the load has been elevated to the desired height.

When it is desired to lower the vehicle, handle 15 is pulled backwardly, thus shifting the pivot of lever 11 to the rear ends of slots 9—9 and at the same time operating lever 26, which, cooperating with rod 25 raises stop lever 23, thus releasing spring 22. Spring 22 being relieved of the pressure of stop lever 23, will operate upon the elevation of dog 16 to exert a push on pawl 17, thus clearing the nose 18 of pawl 17 from the rack and permitting the lowering of dog 16 with the rack until at approximately the end of the stroke of lever 11 spring 22 will exert a pull upon pawl 17, drawing its nose 18 again into engagement with the rack. A slight further movement of lever 11 releases dog 16 from the weight of the load and permits the pull of spring 22 to retract its nose from engagement with the rack and thus permit the elevation of dog 16 to repeat the steps of this operation successively.

Various modifications in the precise form and details of construction will readily suggest themselves to those skilled in the art, but all within the scope of the present invention as claimed.

Having thus fully described my invention, I claim:

1. In a jack, a rack, a dog for operating the rack and pawl means operative both to secure the rack and return the dog to operative position.

2. In a jack, a rack, a lever operated dog for actuating the rack and pawl means oper-

ative both to secure the rack and to return the dog and its lever to operative position.

3. In a jack, a rack, a lever, a dog operated by the lever for actuating the rack, and a pawl mounted upon the lever eccentrically with respect to its pivot to control the rack and operate the lever as specified.

4. In a jack, a rack, a pivoted lever, a dog pivoted to the lever to operate the rack, a pawl pivoted to the lever intermediate the lever pivot and the dog pivot, and resilient means connecting the dog and pawl.

5. A jack comprising a frame, a rack 70
slidable in the frame, a lever having a sliding pivotal mounting in the frame, a dog pivotally mounted on the lever, a pawl pivotally mounted on the lever eccentrically 75
with respect to the latter's pivot, resilient means connecting the dog and pawl, stop means operative on said resilient means and means whereby the shifting of the pivotal mount of the lever relative the frame will 80
operate the stop.

6. A jack comprising a frame, a rack 85
slidable in the frame, arcuate slide pivot-bearing surface in said frame, a lever slidably pivoted on said bearing surfaces, a dog pivoted to the lever to operate the rack, a pawl pivoted to the lever eccentrically with respect to the latter's pivot, resilient means connecting the dog and pawl to control their 90
relation, a stop lever operative on said resilient means and lever means operative by the sliding of the pivotal mount of the first mentioned lever to control said stop lever.

7. A jack comprising a frame, a rack 95
slidable in the frame, arcuate slide pivot-bearing surfaces in said frame, a lever slidably pivoted on said bearing surfaces, a dog pivoted to the lever to operate the rack, a pawl pivoted to the lever eccentrically with respect to the latter's pivot, resilient means connecting the dog and pawl adapted to 100
exert either a pull or push therebetween.

8. A jack comprising a frame, a rack 105
slidable in the frame, arcuate slide pivot-bearing surfaces in said frame, a lever slidably pivoted on said bearing surfaces, a dog pivoted to the lever to operate the rack, a pawl pivoted to the lever eccentrically with respect to the latter's pivot, resilient means connecting the dog and pawl comprising a substantially W-shape spring having its ends secured to said members respectively.

In testimony whereof I affix my signature.

THOMAS WILLIAM BIBB.
